United States Patent Office

Des. 193,097
Patented June 26, 1962

193,097

BASKETBALL BACKSTOP

Richard M. Pohrer, St. Louis, Mo., assignor to Aalco Manufacturing Company, St. Louis, Mo., a corporation of Missouri

Filed June 8, 1961, Ser. No. 65,515

Term of patent 14 years

(Cl. D34—5)

FIG. 1

FIG. 2

FIG. 3

FIGURE 1 is a top plan view of a basketball backstop embodying my new design.

FIGURE 2 is a side elevational view thereof.

FIGURE 3 is a front view thereof.

I claim:

The ornamental design for a basketball backstop, as shown.

References Cited in the file of this patent

UNITED STATES PATENTS

1,924,811 Schulz ----- Aug. 29, 1933
2,553,105 Morey ----- May 15, 1951

OTHER REFERENCES

Sweet's Architectural File, 1954, section 22J/Me, page 8, upper left No. 1102, Glass Backboard.